UNITED STATES PATENT OFFICE.

JONATHAN LUCAS, OF SAVANNAH, GEORGIA, ASSIGNOR TO LUCAS-LAMBORN LOOM CORPORATION, OF NEW YORK, N. Y., A CORPORATION OF NEW YORK.

LOOM.

Original application filed May 7, 1924, Serial No. 711,581. Divided and this application filed February 15, 1927. Serial No. 168,256.

My invention relates to looms and more particularly to looms in which the shuttle is passed back and forth through the warp shed on inversely reciprocating carriers and has for its object to provide a novel and simple coupling mechanism whereby the shuttle is automatically connected with and disconnected from said carriers in alternate sequence. The invention will be fully described hereinafter and the features of novelty will be pointed out in the claims. The present application is a division of another application filed by me in the United States Patent Office, on May 7, 1924, Serial No. 711,581, issued on April 5, 1927 as United States Patent No. 1,623,258.

In the accompanying drawings, which illustrate an example of the invention without defining its limits, Fig. 1 is a front elevation of a loom embodying the novel features; Fig. 2 is a fragmentary front view showing the invention on an enlarged scale; Fig. 3 is a plan view thereof, and Fig. 4 is a section on the line 4—4 of Fig. 2.

The loom comprises a support or frame 15 of conventional construction upon which the operating elements of the loom are mounted as shown in Fig. 1, and which is provided with guiding devices along which carriers for the shuttle are slidably reciprocated to pass said shuttle backward and forward through the warp shed. In the form shown in the drawings, the guiding devices comprise rods 16, properly located in the loom, on which the carriers 17 and 17^a are slidably mounted. The carriers 17 and 17^a are connected by means of links 18 with rocking arms 19 pivotally mounted at 19^a upon the support 15 and in turn connected by means of rods 20 with oppositely disposed cranks 21 forming part of a crank-shaft 22. The latter is journaled on the frame 15 and is operated in any conventional manner to bring about an operation of the parts. The carriers are provided with arms 23 and 23^a respectively arranged in pairs upon said carriers and adapted to alternately support the shuttle 24 in its travel back and forth through the shed. In addition to the parts so far described, the carriers are provided with rocking arms 25 and 25^a respectively, pivoted at 26 and having one end connected at 27 and 27^a with slidable members 28 and 28^a respectively. Other ends of the arms 25 and 25^a are pivotally connected with tripping members 29 and 29^a respectively, said members being provided with a plurality of notches 30 and 30^a adapted to be engaged by resilient members 31 and 31^a to maintain the members 29 and 29^a in adjusted positions, as will appear more fully hereinafter. The carriers are further provided respectively with coupling hooks 32 and 32^a adapted for engagement with the ends 33 and 33^a of a locking latch in the form of a pivoted lever 24 fulcrumed at 35 upon the shuttle 24 as shown in Fig. 2. The lever 34 is provided at its opposite ends with inclined surfaces 36 and 36^a adapted to cooperate respectively with correspondingly inclined ends 37 and 37^a of the members 29 and 29^a. At a central point, the loom is provided with a rocking member 38 pivoted at 39 and connected by means of a pitman 40 with an eccentric 41 mounted upon a driven shaft which may be the crank shaft 22 or any other suitable shaft 22^a in the machine.

Assuming the parts to be in the position indicated in Fig. 2 and the loom to be in operation, the shuttle will be drawn toward the left, because of the fact that the hook 32 is in connection with the end 33 of the locking lever 34. The latter is held in engagement with the hook 32 by reason of the fact that the inclined end 37 of the member 29 is in positive engagement with the inclined surface 36 of the locking latch. At this stage, the end 33^a of the locking latch is above and consequently disengaged from the hook 32^a, so that the carrier 17^a interposes no interference to this movement of the shuttle by the carrier 17. The connection between the shuttle and the carrier 17 through the medium of the hook 32 and the end 33 is maintained throughout the return movement of the shuttle toward the right, in this case until the carriers reach their extreme inner positions. By the time this point in the operation of the machine is reached, the member 38 will have been rocked to a position opposite to that in which it is illustrated in Fig. 2. This change in the position of the member 38 brings its one end into the path of the slidable member 28. Thus, as the carriers approach said extreme inner positions, the member 38 will engage the

rod 28^a and force it to the right in Fig. 2, thereby swinging the rocking arm 25^a upon its pivot and shifting the member 29^a to the left, said member 29^a being held in this adjusted position by the member 37^a, in cooperation with the second notch 30^a. As this movement of the member 29^a takes place its inclined end 37^a will exert a camming effect upon the inclined end 36^a of the locking latch 34 and will force the end 33^a thereof downwardly into locking engagement with the hook 32^a. At the same time, the end 33 of the locking latch 34 will be moved out of connection with the hook 32; as this disconnection of the end 33 from the hook 32 takes place, the inclined end surface 36 will exert a camming action upon the inclined end 37 and consequently will force the member 29 toward the left in Fig. 2. This will rock the arm 25 upon its pivot and will shift the rod 28 toward the right and back to a position ready to be engaged by the member 38 at the proper time. As the operation of the loom now continues, the shuttle will be drawn to the right by the carrier 17^a until it reaches its extreme outer position and will then be shifted back to the position shown in Fig. 2, where it becomes disconnected from the carrier 17^a and connected with the carrier 17 in the manner set forth. These operations are repeated in sequence throughout any given operative period of the loom.

In the form illustrated in the drawings, a positive connection is maintained between the shuttle and the actuating mechanism, through the entire operative paths, of said shuttle. That is to say, throughout half of a given path in one direction and a half of a given path in the return direction, the shuttle is in positive connection with one carrier and throughout the other half of said paths, is in positive connection with the other carrier. The shuttle is thus positively controlled throughout its entire range of movement and consequently is uniformly moved and is free from undesirable variations in speed and at the same time is positively maintained in its intended paths.

Various changes in the specific form shown and described may be made within the scope of the claims without departing from the spirit of the invention.

I claim:

1. A loom comprising a stationary support, a travelling shuttle, guiding devices on said support extending over the operative paths of said shuttle, a pair of carriers arranged to be inversely reciprocated upon said guiding devices for passing said shuttle over said operative paths, a pivoted lever on said shuttle constituting a locking latch, hooks fixed upon said carriers, tripping devices mounted upon said carriers, and mechanism independent of said carriers for actuating the tripping devices of said carriers

in alternate sequence whereby said lever is rocked at a predetermined point in the operative paths of said shuttle to connect it with one of said hooks and simultaneously disconnect it from the other hook. 70

2. A loom comprising a stationary support, a travelling shuttle, guiding devices on said support extending over the operative paths of said shuttle, a pair of carriers arranged to be inversely reciprocated upon said guiding devices for passing said shuttle over said operative paths, a pivoted lever on said shuttle constituting a locking latch, hooks fixed upon said carriers, movable members mounted upon said carriers, a rocking member whereby said movable members are alternately operated to shift the opposite ends of said locking latch respectively into and out of engagement with said hooks and vice versa when the carriers reach their innermost positions and means for actuating said rocking member. 80 85

3. In a loom, the combination of a stationary support, a travelling shuttle, a pair of inversely reciprocated carriers for reciprocating said shuttle over its operative path, coupling means on each of said carriers, a movable coupling device carried by said shuttle and cooperating with said coupling means to connect said shuttle with said carriers, tripping members movably mounted on said carriers, rocking arms on said carriers movably connected with said tripping members, slidable members on said carriers movably connected with said rocking arms and projecting inwardly beyond said carriers, a rocking member mounted on said support, and mechanism for adjusting said rocking member into the path of said slidable members in alternate sequence 90 95 whereby the latter, said rocking arms and tripping members are actuated for shifting said coupling device into and out of engagement with said coupling means in inverse relation, to connect said shuttle with one carrier and simultaneously disconnect it from the other carrier and vice versa. 100 105

4. In a loom, the combination of a stationary support, a travelling shuttle, a pair of inversely reciprocated carriers for reciprocating said shuttle over its operative path, coupling means on each of said carriers, a movable coupling device carried by said shuttle and cooperating with said coupling means to connect said shuttle with said carriers, tripping members movably mounted on said carriers, rocking arms on said carriers movably connected with said tripping members, slidable members on said carriers movably connected with said rocking arms and projecting inwardly beyond said carriers, a rocking member mounted on said support, mechanism for adjusting said rocking member into the path of said slidable members in alternate sequence whereby the 110 115 120 125 130

latter, said rocking arms and tripping members are actuated for shifting said coupling device into and out of engagement with said coupling means in inverse relation, to connect said shuttle with one carrier and simultaneously disconnect it from the other carrier and vice versa, and resilient mem-

bers mounted on said carriers and engaging said tripping members for releasably fixing the latter in their adjusted positions. 10

In testimony whereof I have hereunto set my hand.

JONATHAN LUCAS.
